(57) **CLAIM**

The ornamental design for a internal component for a foldable toy building, as shown and described.

DESCRIPTION

FIG. 1 is a top perspective view of a internal component for a foldable toy building, showing my new design in an assembled configuration;

FIG. 2 is a front elevational view thereof in the assembled configuration;

FIG. 3 is a back elevational view thereof in the assembled configuration;

FIG. 4 is a left elevational view thereof in the assembled configuration, the right elevational view being a mirror image thereof;

FIG. 5 is a top plan view thereof in the assembled configuration;

FIG. 6 is a bottom plan view thereof in the assembled configuration; and,

FIG. 7 is a top plan view thereof, in a flat, unassembled configuration.

1 Claim, 6 Drawing Sheets

FIG. 1

FIG. 2

FIG. 3

FIG. 4

FIG. 5

FIG. 6

FIG. 7
